[57] CLAIM

The ornamental design for a combined beach mat and canopy, as shown and described.

DESCRIPTION

FIG. 1 is a front, top and side perspective view of the mat portion of a combined beach mat and canopy, shown separately for clarity of illustration;

FIG. 2 is a front elevational view thereof;

FIG. 3 is a rear elevational view thereof;

FIG. 4 is a side elevational view thereof, the side opposite being a mirror image of the side shown in FIG. 4;

FIG. 5 is a top plan view thereof;

FIG. 6 is a bottom plan view thereof;

FIG. 7 is an exploded perspective view of the combined beach mat and canopy;

FIG. 8 is a front elevational view of FIG. 7, in unexploded condition; and,

FIG. 9 is a rear elevational view of FIG. 7 in unexploded condition.

FIG. 1

FIG. 2

FIG. 3

FIG. 4

FIG. 5

FIG. 6

FIG. 7

FIG. 9

FIG. 8
